UNITED STATES PATENT OFFICE.

HUGH W. SANFORD, OF KNOXVILLE, TENNESSEE.

WHEEL CONSTRUCTION.

1,088,376.

Specification of Letters Patent. Patented Feb. 24, 1914.

Application filed August 14, 1913. Serial No. 784,798.

To all whom it may concern:

Be it known that I, HUGH W. SANFORD, a citizen of the United States, residing at Knoxville, in the county of Knox and State 5 of Tennessee, have invented certain new and useful Improvements in Wheel Constructions, of which the following is a specification, reference being had therein to the accompanying drawing.

10 This invention relates to an improvement in wheel construction and is designed more particularly for use in connection with mining cars.

The invention may be characterized further as an improvement on that type of wheel and its mounting as shown in patent issued to me on the 2nd of July 1912, No. 1031590.

In the wheels of this type heretofore made, it has been usual and customary to key the hub member of the wheel to the pedestal member of the car body by forming in the hub an annular channel and inserting through the pedestal box casting cross keys 20 or bolts which when in position have their central or intermediate portions resting in the channel of the hub member. In such structures, it has been necessary to form the bolts perfectly straight, and owing to this 25 fact the surface contact between the walls of the channel of the hub is relatively small. The longitudinal vibration of the hub will, owing to the relatively small wearing surface presented between the key or pin, tend 30 to soon destroy or wear the key.

One of the objects of the present invention is to provide a structure wherein a curved key can be employed successfully whereby a relatively extended wearing or abutting surface 35 is presented between the key and the flange of the hub.

A further object of the invention is to reduce friction between the locking parts by the interposition of anti-friction bearings 45 conveniently located between the locking key or bolt and the flange of the hub.

In the accompanying drawings is illustrated an embodiment of the invention, but it is to be understood that the construction 50 shown may be varied materially and the forms changed without departing from the nature and principle of the invention so long as the principles are maintained and embodied in such various modified structures.

Figure 1 is a longitudinal section through the wheel hub and pedestal casting member, showing the invention applied, Fig. 2 is a cross section through the line 2-2 of Fig. 1, Fig. 3 is a view similar to Fig. 1 showing a modified form, and Fig. 4 is a cross section on the line 4-4 of Fig. 3.

The car body is represented in the drawings by the letter A, B designating the axle which, as usual in such structures, is carried by the car body through the intermediate pedestal box or casting C. This casting C is formed substantially cup-shaped and has on its outer periphery or edge a channeled part c formed with an internal key receiving channel c' and an inwardly extending flange c². The side walls of the casting C are conveniently straight, as shown in Fig. 2, at C', thereby reducing the diameter as compared with the other diameter of the casting, the flange and the part c being formed on a true circle, the center of which is the axis of the hub, the flange terminating at the side part C'. The pedestal casting thus formed is somewhat oblong, as shown in Fig. 2, the smaller diameter being slightly greater than the diameter of the hub member presently to be described. The lower portion of the pedestal casting C in line with the part c is conveniently open as at c³, the length of this open part extending from the lower ends of the side members C', while the flange part c⁴ corresponding to the part c² is carried from the ends of the side walls in the curve of a true circle corresponding with the line c², thus corresponding with the flanged portion c⁵ of the pedestal casting part and forming a channel for the purposes presently to be stated.

D designates the hub having conveniently a closed outer end and a bearing flange d at its inner end. This flange d is located a short distance from the extreme end of the hub and has conveniently a vertical bearing face as at d'. The diameter of the flange part d is less than the inner diameter of the cup-shaped pedestal casting, so that the hub can be readily inserted with its flanged end into the said casting.

E designates a series of anti-friction rollers having studs e in their ends, the outer ends of which, when the rolls are in place, enter an annular groove e' in the outer end of the hub.

F designates the metallic plate conven-

110

iently of dish formation having outer and inner horizontal flanges. The outer flange of the end plate is conveniently riveted to the extreme end of the hub part by the rivets 5 f , while the inner end of the plate projects below and serves to retain the end of the roller bearings E in position in the hub when the hub is removed.

Mounted on the inner end of the hub is a 10 circular race way member G conveniently consisting of two correspondingly formed plates having a depending flange g forming one member of a ball bearing. Between the flange g and the flange d of the hub are 15 placed a series of balls H . The bearing G is conveniently, as stated, in two parts, the ends of which are united by outstanding flanges g' riveted together in any convenient manner. The bearing thus formed is so positioned that its outer portion will lie approximately within the plane of the inner part of the key way c' .

J represents the keys or securing bolts formed of metal which may be, although not 20 necessarily restricted, of rectangular cross section. These keys have their central portions bent to conform substantially to the curvature of the hub, while their outer end portions are tangential or substantially 25 straight with reference to the center part. The ends of the keys are beveled and the entire length of the key is such as to extend from the top of the channel c' downwardly into the space between the parts c^4 and c^5 , 30 so that a bearing of ample dimensions is provided for each end of the key, retaining it in position against the end thrusts of the hub. The keys, as will be seen, extending from the seats or flanged part of the pedestal 35 casting into proximity and around the side of the hub, serve as effective locking keys with an extended surface contact between the keys and the hub member, and owing to the position of the ball bearing interposed 40 between the same and the flange d , friction is greatly reduced while the parts are firmly and satisfactorily held in place, practically all wear being eliminated. To retain the 45 keys in place, a wide locking bar K is employed, the same passing through the flange parts c^4 and c^5 , as shown in Fig. 1, the bar occupying a position centrally between the lower ends of the keys. The ends of this 50 bar are conveniently turned down or otherwise formed for securing it in position. When it is desired to remove the hub, all that is necessary is to remove the bar K and the keys J may then be moved about the axis of the hub until the upper straight end lies parallel with the sides C' , as shown in dotted lines in Fig. 4. In this position, the key can be readily removed from the box and the hub removed with its ball bearings.

Any convenient form or shape of hub may 55 be employed and the ball race G applied

owing to its divided character. When it is necessary to remove the roller bearings E , all that is necessary is to remove the rivets holding the cup-shaped member F and slip the same out from the ends of the hub. It 70 may be noted that the hub is prevented from moving inward by the end part contacting with the end of the axle, as is usual.

In Figs. 4 and 5 a structure similar to that of the other figures is shown, but the 75 ball bearing is omitted. Otherwise, the construction is the same, in that the pedestal box C' is substantially the same construction, the axle B' and the hub D' are the same except that the flange d^3 is positioned somewhat forward from that shown in the other figures. The keys J' are designed to engage directly with the flange d^3 . In Fig. 4 the 80 method of removing the key is clearly shown in dotted lines.

As above suggested, the key may be of different cross sections, but the square type is desirable. In connection, however, with the use of the ball bearings between the key and the hub, it has been ascertained that a 90 key of circular cross section may be employed if desired.

As far as I am aware, I am the first to provide a ball bearing for the locking keys between the hub and the pedestal member 95 and also the first to invent a structure wherein a curved key can be readily employed for uniting the hub to the pedestal box. I therefore do not wish to be limited to the detailed construction shown. Obviously the ball bearing can be used with straight keys.

Having thus described my invention, what I claim as new and desire to secure by Letters Patent is:

1. The combination with a pedestal casting member having a part fashioned to receive the end of a wheel hub and formed with a key receiving part, of a hub member having a flanged part, a key interposed between said key receiving portion and flanged part, and an anti-friction bearing with which the key engages.

2. The combination with a pedestal portion having a hub receiving end formed with a key receiving part, of a hub having a portion with which the key is adapted to engage, a key carried by the pedestal part, and an anti-friction bearing between the hub part and the key.

3. The combination with a pedestal part having a portion for receiving the ends of a key, of a hub part having a flange projection, a key interposed between the flange and the said pedestal portion, an anti-friction bearing between the key and the flange, comprising a series of balls, and means for retaining the balls in position.

4. The combination with a pedestal part having a chambered outer end and a key

opening in its wall, of a hub part, a key part insertible through said opening and having a portion bent to conform substantially to the contour of the hub, and means for retaining the key part removably in position.

5. The combination with a pedestal part and a hub part and means for locking the same in position comprising a curved key 10 part and flange members oppositely disposed with relation to the key part for securing the pedestal and hub in position, and means for removably securing the key part in place, substantially as described.

15. 6. The combination with a pedestal member having a channeled upper portion, substantially straight side portions and a flanged lower portion, of a hub member having a flanged part, a plurality of key members curved in part to engage the hub and having relatively straight terminal portions and fitted between the flanges, and means for retaining the key parts removably in position.

25. 7. In a car structure, the combination with an axle and pedestal part, said pedestal part having an integral substantially cup-shaped wall for the reception of the end of the hub part, of a hub part and means 30 exterior of the hub for locking the parts in position, said means comprising a curved key member with means for removably securing the key in place.

8. The combination in a car structure, of 35 an axle and a pedestal part, of a hub and a curved key for locking the hub to the pedestal, said key being insertible and removable through the wall of the pedestal part.

9. The combination with the axle and pedestal part of a plurality of removable curved keys interlocking the parts to secure the same together, the ends of the keys extending tangentially relative to the body thereof.

10. The combination with an axle and 45 pedestal part, of a hub part, a plurality of removable curved keys, means for retaining the keys in position for normally securing the hub to the pedestal, and means for permitting the removal of the keys.

50. 11. The combination with the axle and pedestal part of a hub part having a bearing shoulder and a key part having a portion curved to conform substantially to the curvature of the hub, the pedestal part having an opening in its wall for the insertion and removal of the key, and means at said opening for securing the key part in place.

12. The combination with an axle part 60 and a pedestal part, a hub part projecting into the pedestal part, said hub part being closed at its outer end and having a flanged inner end, of a transversely arranged key member and an anti-friction bearing interposed between said transversely arranged key member and said flange.

13. In a car wheel structure, the combination with a pedestal or body part having its outer end recessed and provided with an inwardly projecting flange, of a hub part having an outwardly extending flange at its inner end, two oppositely disposed keys fitted between said flanges, and means independent of the keys for retaining the same removably in place.

14. In a wheel structure, the combination 75 with a pedestal part and a hub part, of a key member for securing the same in relative position, of an anti-friction bearing interposed between the pedestal part and hub part comprising a divided race way and a 80 series of balls, and means for securing the parts of the race way together.

15. The combination with a pedestal box and a hub, of two oppositely disposed keys having their intermediate portions bent to 85 conform to the contour of one of the members and an interposed removable member for preventing the removal of the keys.

16. In a car, the combination with an 90 axle and pedestal, of a hub removably secured to the axle, a series of rollers in the hub having projecting end parts, and a plate secured within the inner end of the hub and having an outer flange and an inner flange, the latter projecting below the end 95 parts of the rollers, the pedestal having a hollow wall overlying the hub part, and a removable key interposed between the hollow wall of the pedestal and said hub part.

17. The combination with a pedestal member having a part fashioned to receive the end of a wheel hub and formed with a key receiving part, of a hub member having a flanged part, a key interposed between said key receiving portion and flanged part, and 105 a plurality of anti-friction bearings interposed between the key and said flanged part.

18. The combination with a pedestal member having a part fashioned to receive the 110 end of a wheel hub, and having an integral key receiving groove, of a hub member having a flange at its inner end, anti-friction bearings positioned on the hub to engage said flange, a key positioned in the groove of 115 the pedestal member, and a bearing plate interposed between the side of the key and said bearings.

19. In a wheel structure, the combination 120 with a pedestal part, having an opening in its bottom wall, a hub part positioned within the pedestal part, and means removably connecting the hub part to the pedestal part comprising a pair of opposed curved keys insertible and removable through said opening, and means for holding the keys in place.

20. In a wheel structure, the combination 125 with a pedestal part, having an opening in its bottom wall, a hub part positioned within the pedestal part, and means removably 130

connecting the hub part to the pedestal part comprising a pair of opposed curved keys insertible and removâble through said opening, said keys having ends offset from the 5 general curvature of the body thereof, and means interposed between said offset ends to retain the keys in place.

In testimony whereof I affix my signature in presence of two witnesses.

HUGH W. SANFORD.
